UNITED STATES PATENT OFFICE.

FRANCIS X. MALOCSSAY, OF NEW YORK, N. Y., ASSIGNEE TO INTERNATIONAL BANDING MACHINE COMPANY, OF NEW YORK, N. Y., A CORPORATION OF NEW YORK.

CIGAR-PACKING DEVICE

1,403,046.

Specification of Letters Patent. Patented Jan. 10, 1922.

Application filed September 15, 1920. Serial No. 410,434.

To all whom it may concern:

Be it known that I, FRANCIS X. MALOCSSAY, a citizen of the United States, and a resident of the city of New York, county of Westchester, and State of New York, have invented a certain new and useful Improvement in Cigar-Packaging Devices, of which the following is a specification.

The object of this invention is to provide a device by means of which cigars or articles of similar character may be quickly and expeditiously packed in boxes by hand. My invention is particularly applicable as an attachment to cigar banding machines enabling the banded cigars to be quickly packed in boxes after they have been issued from the machine.

With these objects and other objects which may hereinafter appear in view, I have devised the particular arrangement of parts hereinafter set forth and more particularly pointed out in the claims appended hereto.

Reference is to be had to the accompanying drawings forming a part hereof in which—

Figure 1 is a perspective view of my improved cigar packing device;

Figure 2 is a front elevation of the same;

Figure 3 is a plan view of the same;

Figure 4 is a transverse sectional elevation of the same, and

Figure 5 is a transverse sectional elevation of a portion of the device showing the manner in which the box-supporting shelf may be inclined with respect to the table from which the cigars are received.

Throughout the various views of the drawings similar reference characters designate similar parts.

In the preferred embodiment of my invention as disclosed in the accompanying drawings 1 indicates a table which is adapted to support the cigars. This table may, if desired, form a part of, or an extension of a portion of the cigar banding machine from which the banded cigars are ejected. Secured upon the upper face of the table 1 is a plate 2 which is provided with a lateral extension or flap 3 which projects outside of the table 1 and is preferably inclined at an angle to enable the cigars to be removed rapidly therefrom and into a cigar box supported below the same in a manner to be hereinafter described.

Secured to the underside of the table 1

is a pair of spaced-apart supporting brackets 4. At 5 is a shelf-supporting member provided at its side ends with strips 6 terminating in ears 7 which are pivotally mounted in the brackets 4 at 8. At 9 is a cigar box supporting-shelf which is supported at right angles to the shelf-supporting member 5 and is vertically adjustable therein. The shelf 9 is fixed upon supports 10 which are connected at the rear by a plate or strip 11 to which is secured a guide strip 12. This guide strip 12 is vertically movable in a guide which is the nature of a continuous slot 13 formed in the shelf-supporting member 5. By means of the arrangement just described, it will be seen that the shelf 9 is vertically slidable or movable in its supporting member 5. A screw 14 extends through the rear plate 11 of the shelf and through the strip 12. This screw is provided with an enlarged head 15 on its inner side and a wing-nut 16 on its outer side. By tightening the wing nut 16 it will be seen that, the shelf 9 may be fixed in any desired position on its supporting member. The shelf-supporting member 5 is provided with a bracket 17 on its rear side to which is pivotally secured a rod 18, which rod is provided near its outer end with notches 19. These notches are adapted to be engaged by a pin 85 mounted in a bracket 21 secured to the under side of the table 1. By shifting the rod 18 so that one or the other of the notches 19 may be engaged, it will be seen that any desired inclination of the shelf supporting member 5 with the shelf thereon may be obtained. This inclination is particularly desirable at various times to enable the cigars to be more expeditiously placed within the box indicated at 22.

From the foregoing the operation of my improved cigar packing device will be readily understood. The cigars 23 rest upon the plate 2 on the table 1. The shelf is adjusted vertically to suit the depth of the box into which the cigars are to be packed and the box 22 rests upon the shelf 9 with the lid 24 of the box projecting under the flap or extension 3 on the plate 2. The cigars 23 are moved in successive layers into the box until the necessary amount of cigars has been placed therein when the box is removed and another placed in position to receive its required amount of cigars. It will be found that by inclining the shelf 9 substantially as 110

shown in Figure 5 the cigars 23 may be quickly swept from the table down the inclined flap 3 and into the box 22. When the box is held in its inclined position the ends of the cigars strike the front wall of the box and fall into proper position within the box.

As has been heretofore explained the shelf is adjustable vertically and may also be adjusted to lie at various angles to accommodate the various shapes and sizes of cigar boxes used.

From the foregoing it is obvious that my invention is not to be restricted to the exact embodiment shown, but is broad enough to cover all structures coming within the scope of the annexed claims.

What I claim is:

1. A device of the class described comprising a table for supporting merchandise, a shelf adapted to support a receptacle into which the merchandise is adapted to be placed, means for pivotally supporting said shelf adjacent the table, and means for vertically regulating said shelf.
2. A device of the class described comprising a table, a box-supporting shelf, pivotally secured adjacent said table, means for adjusting said shelf vertically to cause the same to hold a box at various heights below the surface of the table and means for caus-

ing said shelf to support a box at an angle to said table.

3. A device of the class described comprising a box supporting shelf, means for raising and lowering the same and means for holding said shelf in an inclined position.

4. A device of the class described comprising a table, a box-supporting shelf, means for holding said shelf at an angle to said table, means for varying the angle at which said shelf may be held and means for raising and lowering said shelf.

5. A device of the class described comprising a table, a shelf-supporting member pivoted thereto and depending therefrom, a shelf slidably mounted on said member and means for regulating the angle at which said shelf-supporting member is held with respect to the table.

6. A device of the class described comprising a table, a shelf-supporting member pivoted thereto, said member having a slot, a shelf having a projecting strip slidable in said slot, means for holding said shelf at an angle to the table and means for regulating the position of the shelf with respect to the table.

Signed at the city, county and State of New York this 2nd day of September, 1920.

FRANCIS X. MALOCSAY.
